UNITED STATES PATENT OFFICE.

EDWIN T. ARMSTRONG, OF ADRIAN, MICHIGAN.

ROTARY DISK VALVE FOR GAS-ENGINES.

1,225,916.

Specification of Letters Patent.

Patented May 15, 1917.

Application filed November 8, 1916. Serial No. 130,288.

To all whom it may concern:

Be it known that I, EDWIN T. ARMSTRONG, a citizen of the United States, residing at Adrian, in the county of Lenawee and State of Michigan, have invented a new and useful Rotary Disk Valve for Gas-Engines, of which the following is a specification.

This invention relates to new and useful improvements in rotary disk valves for internal combustion engines.

The principal object of the invention is to produce a simply constructed noiseless valve which may be operated without the use of springs or cams, to take the place of the usual puppet or sleeve valves.

A secondary object is to produce a valve, the operation of which will be mechanically positive at all times and will not be affected by the deposits of carbon.

Still another object is to provide a valve which, while having large gas passageways, will be so constructed that it will be absolutely gastight except when the ports are opened.

With these and other objects in view the invention resides in the novel features of construction, combination and arrangement of parts which will be hereinafter more particularly described and claimed, and shown in the drawings wherein:

Figure 1 represents a vertical transverse section through a portion of an internal combustion engine, certain parts of which, including the top plate, are removed for the sake of illustration;

Fig. 2 is a bottom plan view of the uppermost valve disk;

Fig. 3 is a similar view of the ring which surrounds the rotary valve head;

Fig. 4 is a top plan view of the lowermost disk;

Fig. 5 is a similar view of the valve head; and

Fig. 6 is a vertical sectional view through the several parts of the invention.

In the preferred embodiment of my invention which is illustrated in the accompanying drawings, wherein similar reference characters designate like parts throughout the several views, it will be noted that the valve is in the casing C of the engine adjacent the inlet and outlet to and from the cylinder C' in which the piston P reciprocates. Fig. 1 shows the inlet 1 from the intake manifold and the outlet 2 leading to the exhaust manifold on the same side of

the engine, these openings communicating with openings 3 and 4 respectively formed in a circular plate or valve disk 5 which is disposed in a seat 5' in the upper end of the engine casing directly over said openings 1 and 2. It will be noted that the lateral walls 6 of each of the openings 3 and 4 are the parts of radii of the circle which forms the periphery of the disk, and that the curved sides 7 are parts of concentric circles whose center is the center of the disk.

Upon this disk 5 is placed a ring 8 whose outer diameter is the same as that of the disk 5 with which it contacts. A second disk 9 also being of a diameter to closely fit the seat 5' rests upon the ring 8. The last named disk 9 also has a pair of openings 10 and 11 which align with the openings 3 and 4; the lateral walls 12 of these openings 10 and 11 as well as the curved walls 13 are formed substantially as the corresponding walls 6 and 7 of the openings in the first mentioned disk.

In order that these openings 3 and 4 may be held in registration with the openings 10 and 11 respectively, a plurality of apertures 14 are formed in the disks adjacent the edges, said ring 8 also having similar apertures, all of which are adapted to align for the reception of the machine bolts 15, the threaded ends of which are screwed into the casing C. Before, however, the top disk 9 is screwed down upon the ring 8, the valve head is placed in position therebetween, the latter consisting of a circular disk-like plate 16 of a diameter substantially the same or slightly smaller than the inner diameter of the ring 8, and a thickness approximately equal to that of said ring. The head 16 has a valve stem 17 fixed to its lower face and in its center, said stem extending through an opening 18 in the center of the lowermost disk 5. The head further has a single opening 19 formed therethrough, said opening having walls 20 which are parts of the radii of the periphery of the disk, and whose curved walls are parts of concentric circles, the center of which is the center of the disk. Thus when the valve stem 17 is caused to rotate, the valve head 16 will simultaneously rotate between the upper and lower disks, and thereby open or close the aligned openings therein.

The valve stem 17 extends downwardly into the crank case of the engine where it is provided with a beveled gear 21, the teeth

of which mesh with the teeth on a second beveled gear (not shown) which is carried by one face of the spur gear 22, the latter in turn being in mesh with a second spur gear 23. Both of these gears 22 and 23 are of the same diameter, the latter being disposed in engagement with a gear 24 whose diameter is substantially one-half of that of the other, this last mentioned gear 24 being mounted on the crank shaft S to rotate therewith. Through this train of gears the motion of the crank shaft is transmitted to the valve stem and thence to the valve head and is suitably controlled through the various sized gears to permit the openings in the valve head and valve disks to register at the proper moments.

As the piston P moves from its highest to its lowest point after an explosion, the valve head will be rotated to bring its opening in alignment with the openings or ports 3 and 10 in the disks which are disposed above and below the same, thereby allowing the exhaust gases to be forced out into the exhaust manifold by the next upstroke of said piston. The moment the piston reaches its highest point the opening in the valve head will have moved beyond the edges of the ports 3 and 11, and as the piston starts its next down stroke this opening 19 will commence to register with the ports 4 and 11, thus permitting a charge of gas to be drawn into the cylinder C'. Continued movement of the crank shaft of the engine causes the valve head to rotate to move its opening out of alignment with the other openings in the valve disks, the parts being so disposed during the compression and explosion of the gases, the latter event taking place when the opening 19 is midway between the ports in the valve disks. To facilitate the rotation of the valve head and to prevent the same from sticking, oil grooves 25 and 26 are formed in the upper and lower faces of the disks 5 and 9 respectively. These grooves extend from the peripheries of the disks to substantially the centers thereof, thus permitting oil to be spread over both faces of the valve head and thoroughly lubricate the same. The upper face of the valve disk 9 is slightly convexed as illustrated in Fig. 1 to prevent the same from warping, and otherwise strengthen it to receive the force of the explosion of the gases.

From the foregoing description, it will be

seen that a very simply constructed rotary valve has been produced which will take the place of the usual sleeve or puppet valves and will operate much more efficiently.

I claim:

1. The combination with an engine having a seat therein; of a valve disk disposed in said seat and having a central aperture and a pair of openings spaced outwardly from said aperture, a second valve disk spaced from the first and having a pair of openings aligned with those therein, a valve head comprising a flat circular plate disposed between said disks and having a single opening adapted to register with either of the aligned openings in the disks, a valve stem connected with the valve head and extended through said central aperture into the crank case of said engine, a beveled gear carried by the inner end of said stem, a spur gear, a second beveled gear carried by said spur gear to mesh with the first beveled gear, a second spur gear in mesh with the first mentioned spur gear, each of said gears being of the same size, and a pinion carried by the crank shaft of said engine and meshing with the second spur gear, said pinion being one-half the size of said gear.

2. The combination with an engine having a seat therein; of a valve disk disposed in said seat and comprising a flat circular plate, said disk having a central aperture and a pair of openings spaced outwardly from said aperture, a second valve disk also disposed in said seat and comprising a circular plate having a pair of openings aligned with the openings in the first mentioned disk, the inner face of said plate being flat and its outer face convex, a ring of a diameter equal to the diameter of said disks and disposed therebetween, fastening elements connecting said disk and ring to the engine, a valve head in the form of a flat circular plate disposed within said ring, said head being of a diameter substantially equal to the opening in said ring and of approximately the same thickness as said ring and having a single opening therein, a valve stem extended through said central aperture and connected to the valve head centrally thereof, and means for rotating said valve head to move its opening into registration with either of the openings in said disks.

EDWIN T. ARMSTRONG.
